UNITED STATES PATENT OFFICE.

EARL POOLER, OF SEATTLE, WASHINGTON.

FILLING-BLOCK FOR PHONOGRAPH-RECORD CABINETS.

1,030,534.

Specification of Letters Patent. Patented June 25, 1912.

Application filed September 12, 1911. Serial No. 648,992.

To all whom it may concern:

Be it known that I, EARL POOLER, a citizen of the United States, residing at Seattle, in the county of King and State of Washington, have invented certain new and useful Improvements in Filling-Blocks for Phonograph-Record Cabinets, of which the following is a specification.

This invention relates to phonograph disk-record cabinets and has for its object 10 the provision of means to adapt a cabinet having stationary shelves for the filing of records to receive disk records of various diameters therein.

15 While the device is equally applicable to any filing cabinet for disk records having suitably formed shelves, a further object of the invention is to adapt the same to the cabinet illustrated in my prior Patent No. 20 980,124.

The invention consists in the novel construction of a filling block for the shelves of phonograph disk record cabinets and the combination and adaptation thereof with 25 a cabinet as will be hereinafter described and claimed.

In the views accompanying this application, Figure 1 is a front elevational view of a filing cabinet for disk records showing an 30 embodiment of the invention in operative position therein; and Fig. 2 is a perspective view of one of the said filling blocks.

Referring to said drawings, the reference 35 numeral 1 designates a phonograph record cabinet having provision for the storing of disk records between lower and upper shelves 2 and 3, respectively, provided with suitably spaced parallel transverse grooves 4 in their respective upper and lower surfaces to receive the peripheral edges of the 40 disk records R. Rectangularly shaped filling blocks 5, see Fig. 2, are provided for said lower shelves 2 which are each formed upon their upper sides with a plurality of 45 parallel transverse grooves 6 of the same size and character as said grooves 4. Upon the underside of each said block they are each provided with a transverse ridge 7 adjacent each of the lateral sides positioned directly subjacent to a selected groove 6 upon 50 its upper surface. The said ridges 7 are formed to interfit within grooves 4 of the

shelves 2 or the grooves 6 of equivalent blocks 5.

The functions of the invention may be 55 described as follows: Phonograph disk records are usually made in certain standard sizes varying in multiples of two inches in their diameters, as twelve, ten and eight inch records. In arranging the shelves in a record cabinet it is found more convenient instead of providing shelves of suitable distances apart to accommodate the respective sizes of records to furnish shelves capable of receiving records of the maximum diameters and to provide one or more filling blocks 60 to rest upon the lower shelves 2 to reduce the space between the latter and the upper shelf 3 to adapt them to receive the smaller sizes.

In Fig. 1 is illustrated a cabinet normally 70 adapted to receive twelve-inch records R between its upper and lower shelves and at A is shown a filling block reducing the space therebetween to receive ten-inch records while at B are shown two such superposed 75 blocks further reducing the space to accommodate eight-inch records. The ridges 7 insure that the grooves of the blocks are retained in proper alignment with the grooves upon the underside of the upper shelf 3 and 80 by frictional engagement maintain the same in selected positions.

It is obvious that the blocks may be made of widths to occupy any desired space along the shelf and that they may be arranged in 85 various ways and combinations to carry out the purpose of the invention.

What I claim, is—

1. In a phonograph record cabinet provided with grooved top and bottom shelves 90 for the reception of disk records, identical filling blocks each provided with parallel grooves upon its upper face and corresponding with the said shelf grooves, each of said blocks being also provided with downwardly 95 directed projections upon the lower side thereof and in vertical alignment with some of said upper face grooves, said downward projections adapted for engagement within some of the grooves of said bottom shelf 100 and another similar block when assembled in superposed relations upon said bottom shelf.

2. A filling block for phonographic rec-

ord cabinets being of a width equal to the difference in diameters of different sized regulation records, said block provided with equally spaced parallel grooves upon its upper face, downward projections provided upon the lower face of said block in vertical alignment with some of said top grooves and said downward projections adapted for en-

gagement within grooves of similar blocks when placed in a superposed relation therewith. 10

EARL POOLER.
